CONTACT RECTIFIER

Richard C. Hitchcock, Bloomfield, N. J., assignor to Westinghouse Electric & Manufacturing Company, East Pittsburgh, Pa., a corporation of Pennsylvania

Application June 1, 1935, Serial No. 24,529

7 Claims. (Cl. 175—366)

My invention relates to rectifiers and especially to the rectifiers of the contact type.

5 An object of my invention is to provide a rectifier suitable for use with currents of the order of microamperes.

Another object of my invention is to provide a contact rectifier bridge having a greatly reduced electrostatic capacity over the standard rectifier bridges now in use.

10 Another object of my invention is to have a rectifier for small currents which operates at high current densities.

Other objects of my invention will become evident from the following detailed description taken in conjunction with the accompanying drawing in which:

Figure 1 is a top plan view of a rectifier bridge embodying my invention.

Fig. 2 is a view on line II—II of Fig. 1 with parts in section and in elevation.

Fig. 3 is an enlarged view of the rectifier portions of Fig. 2.

Fig. 4 is a modification of the rectifier construction of Fig. 2.

Fig. 5 is a still further modification of the rectifier construction of Fig. 2.

Fig. 6 is a diagrammatic view of the circuit of the bridge in Figs. 1, 2, 4 and 5.

Fig. 7 is a top view of a rectifier element similar in shape to those of Fig. 5 but of smaller diameter.

Figs. 8 and 9 are modifications of the rectifying surfaces and contact arms of those shown in Fig. 2.

35 The standard construction of contact rectifiers such as represented by the most important class therein is a copper disc generally about three-fourths to one and one-half inches in diameter with one side oxidized. It has been found, however, that these copper discs have a very increased resistance for small currents. A three-fourths inch diameter disc will have 20 ohms resistance at 20 milliamperes, 30 ohms at 10 milliamperes and then greatly increase to about 800 ohms as the current approaches zero. This varying and increasing resistance when the current is below a milliampere has disadvantages due to the big change in resistance with small fluctuations in the current strength.

50 Another disadvantage with the standard construction is that due to the extensive area of the rectifying disc a bridge would have a large electrostatic capacity and if the alternating current increased in frequency above the commercial 60 cycles, there was a tendency of the alternating current to pass directly through the bridge and not to pass through the load.

Accordingly my invention contemplates increasing the current density and reducing the 60 electrostatic capacity by decreasing the rectify-

ing area in a rectifier bridge. This reduction in area provides for working at a better portion of the resistance to current curve. The smaller area of the rectifying elements also permits the use of the bridge with higher frequencies even of the order of radio broadcast frequencies.

5 In Fig. 1 I have disclosed one preferred embodiment of my invention. The ring 10 is of any suitable insulating material and has preferably attached to its upper annular surface 11 a plurality of inwardly extending arms 12, 13 and 14. In the case of a bridge construction, these arms may be limited to the three shown, although any number, especially a multiple of three, might be provided. In general four arms are required, +, —, AC, AC; in the special case of Fig. 1, the + is the clamping members, hence only three other arms are required. These arms extend towards the central axis and are preferably bent downward as shown in Figs. 2 and 3. 20 The inner ends of these arms are in serial contact relation and are superimposed on one another as disclosed in Figs. 2 and 3. I prefer to have the rectifying junction only at the inner ends of these arms. As shown more clearly in Fig. 3, the end of the arm 14 has a small copper oxide rectifying layer on its upper end surface 15. The next arm 13 below it preferably has both its upper end surface 16 and lower end surface 17 oxidized. The lower surface of the arm 12 also has the oxidized surface 18 thereon. Various ways may obviously be used to keep these contact surfaces in compressed engagement, but one that is both simple and effective is disclosed in Fig. 2 wherein a contact bar 20 preferably of copper extends across the under side of the annular ring 10 and has a central raised portion 21 upon which the oxide junction 18 rests and makes contact therewith. Another bar 22, also preferably of copper, extends across the top of the annular ring and has a conductive screw 23 passing centrally therethrough and making contact under any desired pressure with the uppermost arm 14. Bolts 24 extend through the ring 10 to connect the bars 20 and 22 and also to 40 bind them securely to the ring 10. These bolts pass through suitable spacers 29. Suitable connections 25 may be made to the bars and also connections 26, 27 and 28 to the arms 12, 13 and 14, respectively. 45

It will be noted that the structure described in Figs. 1, 2 and 3 forms a very simplified full-wave rectifying bridge with the four necessary connections. The actual rectifying surface is very small and the bridge accordingly has a 55 greatly reduced capacity over the standard construction.

The connections to the bridge are made by connecting the alternating current to the arms 12 and 14 and the positive of the load to the terminal 60

25 of the bars 20, 22 and the negative load to the arm 13. If the alternating current enters by the arm 14 during one-half cycle, it will pass upwardly through the rectifying junction 15 to the screw 23 and bar 22 and through the load back to the arm 13 where it passes through the rectifying junction 17 to the arm 12 to the source of current. On the next reversal of current the current will enter by the arm 12 and pass through the rectifying junction 18 to the bar 20 and through the load and then back to the arm 13 and then through the rectifying junction 16 to the arm 14 back to the source of current. This type of bridge is diagrammatically illustrated in Fig. 6.

15 Fig. 4 illustrates a still further modification and is, in fact, a little more simplified than that of Fig. 2. A U-shaped conductive member 30 has a screw 31 passing through the end of one of its arms and compressing three conductive arms 32, 33 and 34 between the tip of its screw and the other arm of the U-shaped member 30. These arms 32, 33 and 34 have the copper oxide surfaces 35, 36, 37 and 38 arranged similar to that illustrated in Fig. 3.

25 Fig. 5 illustrates a still further modification in which the rectifying surfaces are made separate from the contact arms. In this figure, four tiny rectifying units 40, 41, 42 and 43 have one of their surfaces oxidized. These rectifying units may be little cylinders having a diameter such as that actually represented in Fig. 7. The contact arms 44, 45, 46 are placed between these four rectifying units and any suitable connecting means, such as the U-shaped member 47, connects the upper and lower units. Although various arrangements of the outside surface and contact arms may be made, I prefer to have the outside surface of the unit 40 contact with the arm 44 and to have both the outside surfaces of the units 41 and 42 contact with the arm 45 and the copper oxide surface 43 contact with the arm 46. In this specific arrangement the alternating current connections will be made to the arms 44 and 46, while the positive terminal of the load is made 45 to the U-shaped member 47 and the negative terminal of the load to the arm 45.

In Fig. 8 I have disclosed how a suitable contact arm 50 may have a still further reduced extension 51 extending from it and then have a small area 52 on this extension 51 oxidized for the rectifying junction. The larger area of the arm 50 makes the assemblage of the device easy. It is possible, however, to have the arm the same width as extension 51 throughout and only to oxidize a tiny area at one end.

50 Another modification is disclosed in Fig. 9 wherein the broad contact arm 60 is tapered down to a small area 61 at the very end and the upper surface of this end oxidized.

60 Other modifications may be made of the shape of the rectifying arms and rectifying units. The arms 44, 45 and 46, for example, may be depressed at their ends to hold the rectifying units 40, 41, 42 and 43 in depressions. Various suitable materials may be used. The arms 44, 45 and 46, for example, may be of some impressionable material, such as lead, that can be squeezed under pressure into a tight contact with the rectifying units. While I have described the contact rectifier as of the copper and copper oxide type, other

less successful types of contact rectifier materials can be used.

An examination of the drawing will clearly disclose that the end of the contact arms in Figs. 1 through 4 and 6 to 9 and also the rectifying units in Figs. 5 and 7 can be made very small. The cross section of the rectifying surface is preferably below that of a square $\frac{1}{16}$ of an inch on a side or a circle $\frac{1}{16}$ inch in diameter. The invention is especially adapted for an actual 10 rectifying surface less than .016 square inch. This last dimension is approximately that of a square $\frac{1}{16}$ inch on a side.

In spite of the tiny rectifying surface, it will be noted that the devices illustrated can be very 15 easily assembled due to their large contact arms and the ease with which electrical connections can be made to these contact arms.

Although I have shown and described certain 20 specific embodiments of my invention, I am fully aware that many modifications thereof are possible. My invention therefore, is not to be restricted except insofar as is necessitated by the prior art.

I claim as my invention:

25 1. A contact rectifier arm of copper having a greatly reduced portion at one end and an oxidized surface limited to said greatly reduced portion.

30 2. A contact rectifier arm having a greatly reduced portion at one end and an oxidized surface only on said greatly reduced portion, said oxidized surface having an area of less than .016 square inch.

35 3. A contact rectifier bridge comprising three arms in radial arrangement with an end of one between the adjacent ends of the other two and contact means joining the outside surfaces of said two, said one of said arms having two rectifying contact surfaces and said other two arms having rectifying contact surfaces on the contact side remote from said arm with the two rectifying contact surfaces.

40 4. A contact rectifier bridge comprising a plurality of copper arms, each having a portion of one end portion superficially oxidized, said oxidized ends being superposed in contact and said arms being disposed in radial arrangement.

45 5. A contact rectifier bridge comprising three copper arms in radial arrangement with an end of one between the adjacent ends of the other two and contact means joining the outside surfaces of said two, said one of said arms having two oxidized contact surfaces and said other two arms having oxidized contact surfaces on the contact side remote from said arm with the two oxidized contact surfaces.

55 6. A contact rectifier bridge comprising a plurality of copper arms, each having a portion of one end portion superficially oxidized, said oxidized ends being superposed in aligned contact and with said arms radiating therefrom, and means maintaining said ends in aligned contact.

60 7. A contact rectifier bridge comprising a plurality of metal contact arms, each having a portion of one end portion having a surface layer adapted to produce a rectifying junction, said ends with surface layers being superposed in contact and said arms being disposed in radial arrangement.

RICHARD C. HITCHCOCK.
